DESIGN FOR A CABINET FOR COIN OPERATED SIMULATED RACE GAME

George A. Gast, Chicago, Ill., assignor to Raymond T. Moloney, Chicago, Ill.

Application April 8, 1936, Serial No. 62,021

Term of patent 14 years

To all whom it may concern:

Be it known that I, George A. Gast, a citizen of the United States, residing at Chicago, in the county of Cook and State of Illinois, have invented a new, original, and ornamental Design for a Cabinet for Coin Operated Simulated Race Game, of which the following is a specification, reference being had to the accompanying drawing, forming part thereof.

The drawing shows a perspective view of my design for a cabinet for coin operated simulated race game.

The ornamentation of the opposite side of the cabinet is the same as that of the side shown.

I claim:

The ornamental design for a cabinet for coin operated simulated race game, as shown and described.

GEORGE A. GAST.
